UNITED STATES PATENT OFFICE

92,458

DESIGN FOR A DISH OR SIMILAR ARTICLE

Solomon Forman, New York, N. Y.

Application March 21, 1934, Serial No. 51,121

Term of patent 3½ years

To all whom it may concern:

Be it known that SOLOMON FORMAN, a citizen of the United States, and resident of New York city, in the county of New York and State of New York, has invented a new, original, and ornamental Design for a Dish or Similar Article, of which the following is a specification, reference being had to the accompanying drawing, forming part thereof, in which,

Fig. 1 is a top plan view of a dish embodying my new design;

Fig. 2 is a side elevational view partly cross-sectioned.

I claim:

The ornamental design for a dish or similar article, substantially as shown.

Dated, New York, March 16, 1934.

SOLOMON FORMAN.
